UNITED STATES PATENT OFFICE.

WILLIAM GEORGE ANDERSON, OF WHITEHEAD, IRELAND.

TOY BUILDING-BLOCKS.

1,298,855.

Specification of Letters Patent.

Patented Apr. 1, 1919.

Application filed June 5, 1918. Serial No. 238,249.

To all whom it may concern:

Be it known that I, WILLIAM GEORGE ANDERSON, a subject of the King of Great Britain and Ireland, residing at Whitehead, 5 county Antrim, Ireland, have invented certain new and useful Improvements in Toy Building-Blocks, of which the following is a specification.

This invention relates to toy building blocks with which models of houses, buildings, and the like, can be built from a number of blocks, or pieces, its object being to provide improvements in blocks of the class having interlocking tongues and grooves, for 10 example, such as described in the specification of my prior United States Patent Number 1236896.

Under the present invention I provide corner pieces and pieces adapted to extend 20 between parallel walls, to tie same, comprising interlocking pieces the pieces having each, on the upper and under sides, a longitudinal tongue and a transverse groove which is cut at least twice as deep as the 25 tongue. The transverse grooves are cut at such distance from the end of the block and to such depth that, when the pieces are interlocked at right angles, the tongue of the one piece engages the groove of the other 30 piece so that the outer side of the one piece is flush with the end of the other piece. The corner pieces have a transverse groove at one 35 end only while binding pieces, or tie pieces, between parallel walls have the transverse grooves at both ends of the piece.

The tongues and grooves of the pieces co-operate to bind the pieces together when an upper piece is superimposed upon a lower piece, so that movement of the interlocked 40 pieces in any horizontal direction is prevented.

Binding and tie pieces, as above described, 45 may be used as parapet pieces for walls, or as eaves pieces for roofs, or they may be made to form any other desired finish to, or part of, a wall. They may also, if desired, be made with their tongues and grooves terminating short of their ends and sides and engaging with corresponding pieces, having 50 their tongues and grooves also terminating as described, so that the tongues and grooves will be concealed when the pieces are in position on or in, the wall.

Starting or finishing, or base, or parapet 55 pieces, or other pieces, may have the invention applied to one upper or under side only

of the piece, and the other side may be solid or may have a longitudinal groove and (or) a transverse groove, according to the nature of the piece with which it is to be engaged. 60

In order that the invention may be clearly understood I have hereunto appended two explanatory sheets of drawings whereon I have shown some examples of my improved interlocking corner blocks and binding 65 blocks.

Figure 1 shows an isometric view of the interlocking corner blocks in accordance with my invention and also shows a binding or tie piece and an eaves piece made under 70 the invention.

Fig. 2 is an isometric view showing the interlocking corner blocks in position and showing how the tongues and grooves of the under blocks are concealed at each side of 75 the corner.

Fig. 3 is a similar view to Fig. 2 but with two corner blocks shown in position for interlocking.

Fig. 4 is a view of another modification of 80 tie piece and eaves piece in which the tongues of the blocks are concealed at the side of the wall.

Figs. 5 and 5^a are detail side elevation and plan view respectively of one of the corner 85 pieces, shown in Fig. 1.

Figs. 6 and 6^a are respectively end elevation and plan of the corner piece shown in Figs. 2 and 3 and showing a double grooved piece connected therewith, and superimposed on a tie piece.

Referring to the drawings:

Corner piece *a* and pieces *b*, adapted to extend between parallel walls to tie same, 95 have each on the upper and under sides a longitudinal tongue *c* and a transverse groove *d* which is cut at least twice as deep as the tongue, the transverse grooves *d* being cut at such distance from the end of the blocks *a* or *b*, as the case may be, that when interlocked at right angles with either pieces *a* or *b*, the tongue of the one piece, for example *a* will engage the groove of the other piece *b* so that the outer side of the piece *a* will be flush with the end of the piece *b*. 105 The corner pieces *a* have a transverse groove *d* at one end only while the binding pieces, or tie pieces, *b*, for binding parallel walls, have the transverse grooves *d* at both ends of the piece. (See Fig. 1.)

The tongues and grooves co-operate to bind the pieces together when an upper

piece is superimposed upon lower pieces, as shown at Fig. 5, and the corner pieces co-operate with double grooved wall pieces *f* and double tongued wall pieces *g* which fill 5 in between the corner pieces. The grooves *f*¹ of the pieces *f* are engaged by the tongues *g*¹ of the next course of wall bricks *g*, the pieces *f* and *g* being used in alternate courses in building a wall. The use of corner pieces as described prevents movements 10 of the interlocked pieces in any horizontal direction.

Binding and tie pieces *b* as above described may be used, as in the example 15 shown, as eaves pieces *k* for roofs, or they may be made to form any other desired finish to, or part of, a wall.

The corner pieces, such as *a*¹, and tie pieces, such as *b*¹, may be made with a 20 groove *d*¹ in one side of each block instead of across the top and bottom of the block, and with their tongues terminating short of their ends, as shown at Figs. 2, 3, 4, 6, and 25 6^a, and engaging with corresponding pieces, having their tongues terminating and grooves made as described, so that all the tongues and grooves will be concealed when the pieces are in position on, or in, the wall.

Starting or finishing, or base, or parapet 30 pieces, or other pieces, may have the invention applied to one side only of each piece, as shown by the bottom blocks *f*² and *g*² of Figs. 2 and 3 where the grooves and tongues are on the top side only, the bottom being 35 solid.

Having now fully described my invention, what I claim and desire to secure by Letters Patent is:—

1. For use in building toy houses and 40 buildings, interlocking blocks for uniting the walls, having on their upper and under sides a longitudinal tongue and a transverse groove.

2. For use in building toy houses and 45 buildings, interlocking blocks for uniting the walls having on their upper and under sides a longitudinal tongue and a transverse groove the depth of the groove being equal to the height of the tongue.

Copies of this patent may be obtained for five cents each, by addressing the "Commissioner of Patents, Washington, D. C."

3. For use in building toy houses and 50 buildings, interlocking blocks forming corner pieces for uniting the walls having on their upper and under sides a longitudinal tongue and a transverse groove, the groove being formed at such a distance from the 55 end of the block that when blocks are superposed and interlocked at right angles, the outer side of one block is flush with the end of another block.

4. For use in building toy houses and 60 buildings, interlocking blocks forming corner pieces for uniting the walls having on their upper and under sides a longitudinal tongue and a transverse groove, the groove being formed at such a distance from the 65 end of the block that when blocks are superposed and interlocked at right angles the tongue of one block engages the groove of another block to bring the outer side of the one block flush with the end of the other 70 block.

5. For use in building toy houses and 75 buildings, interlocking blocks forming corner pieces for uniting the walls having on their upper and under sides a longitudinal tongue and on the inner side of the block a transverse groove, the tongue terminating short of the end of the block, the groove being formed at such a distance from the end of the block that when blocks are superposed and interlocked at right angles, the tongue of the block engages the groove of another block to bring the outer side of the one block flush with the end of the other block. 85

6. For use in building toy houses and 90 buildings, interlocking blocks each having a plurality of longitudinal tongues and a plurality of transverse grooves the tongues and grooves terminating short of the ends and sides of the blocks.

In testimony whereof I affix my signature in presence of two witnesses.

WILLIAM GEORGE ANDERSON.
